UNITED STATES PATENT OFFICE.

ALBERT E. EVANS, OF PITTSBURGH, PENNSYLVANIA, ASSIGNOR TO PITTSBURGH PLATE GLASS COMPANY, A CORPORATION OF PENNSYLVANIA.

APPARATUS FOR SURFACING GLASS AND THE LIKE.

Application filed June 5, 1923. Serial No. 643,501.

The invention relates to apparatus for surfacing (grinding or polishing) sheets of material, such as glass, and the like, the apparatus having its greatest utility in connection with the grinding and polishing of plate glass in a straight-away operation in which the glass to be surfaced, supported on trucks or carriers, is passed beneath a series of grinding and polishing machines. The invention involves a modification of the apparatus of my application, Serial No. 636,327, filed May 3, 1923, in that the driving motor, or other power means, instead of forming a part of the removable self-contained surfacing unit is separate therefrom, being mounted either on the inner end of the counterbalancing lever or on the fixed framework of the machine and having driving connections with the surfacing unit of such character that they may be readily disconnected when it is desired to remove the surfacing unit from the machine. The power transmission means between the motor, or the drive shaft on the framework, and surfacing unit is preferably a belt or sprocket chain, but any other suitable transmission means, not interfered with by the up and down movements of the unit and readily disconnectable therefrom might be employed. Certain embodiments of the invention are illustrated in the accompanying drawings wherein:

Figure 1 is a side elevation of the machine. Fig. 2 is a front elevation. Fig. 3 is a plan view. Fig. 4 is a section on the line IV—IV of Fig. 1. And Figs. 5 to 8 are side elevations illustrating modifications.

Referring to the construction as illustrated in Figs. 1 to 4, the glass to be ground or polished is carried upon a series of trucks or tables 1, mounted upon the tracks 2, the tables being moved along the tracks by means of the racks 3 secured to the lower sides of the trucks and engaged by the spur gears 4 driven from the pinions 5 carried upon transverse shafts 6.

The framework of the machine is similar to that shown in my application referred to being made up of channels 7, 8, 9 and 10 riveted or bolted together and carrying the bracket or support 11 which is preferably a steel casting. Extending transversely of the upper end of this casting is a pivot rod 12 and upon this is mounted the lever 13, provided at one end with a pair of hook shaped

members 14, and at the other end counterbalanced by means of the rod 15. The surfacing unit which is carried by the lever consists of a tubular support 16 provided with suitable bearings in which is journaled 60 the runner shaft 17 carrying at its lower end the runner 18 and at its upper end provided with a bevel gear 19.

The support 16 also carries at its upper end a gear casing 20 in which is journaled a 65 shaft 21 carrying a bevel gear 22 for driving the gear 19 and a pulley 23. The pulley 23 is driven by the belt 24 passing around the drive pulley 25 of the motor 26.

The motor 26 is mounted upon the inner 70 end of the lever 13 and serves to counterbalance the surfacing unit carried by the outer end of such lever. The motor is secured to the lever by means of the bolts 27 working in suitable slots in the base of the 75 motor and is adjustable toward and from the surfacing unit in order to adjust the tension of the belt by means of the bolts 28 and 29.

The hook shaped members 14 at the outer 80 end of the lever 13 engage the trunnions 30, extending laterally from the support 16, and preferably made integral therewith. In order to prevent the accidental displacement 85 of the trunnions from the members 14, the caps 31 are provided pivoted at one end to the lever and secured at the other end by means of suitable clamping bolts 32. The lower end of the support 16 is secured by means of a link 33 pivoted on a transverse 90 rod 34 carried by the casting 11 and having its outer ends hook shaped as indicated at 35 and fitting over laterally extending trunnions 36 carried by the support. In this manner the support 16 is maintained at all 95 times in a true vertical position and at the same time free to oscillate vertically.

Pivoted to the inner end of the lever 13 is the yoke 37 (Fig. 4) and extending through the bottom of this yoke is the adjusting rod 100 15 provided at its upper end with a head 38 with the spring 39 interposed between such head and the bottom of the yoke. The lower portion of the rod is threaded so that the tension of the spring 39 may be adjusted by 105 means of the hand wheel 40 which is threaded onto the rod. Lying above the hand wheel 40 is the sleeve 41 pivotally mounted to oscillate in the brackets 42 carried by the channel bars 9.

It will be seen from the foregoing that the surfacing unit is counterbalanced by the weight of the motor and by the spring 39 which is subject to adjustment so that the force exerted by the runner upon the glass may be regulated to suit requirements. In case it becomes necessary to repair or replace the runner bars, or to repair the driving mechanism of the surfacing unit, this may be very readily accomplished upon disconnecting the belt 24 and removing the surfacing unit bodily, this latter function being accomplished by means of an overhead crane or some equivalent apparatus. Spare surfacing units can be kept ready for use so that upon the removal of one unit, it may be replaced by another without waiting to repair the unit which is removed.

Fig. 5 illustrates a modification in which the motor 43 is mounted upon the fixed framework of the machine instead of being carried upon the counterbalancing lever 44. The belt drive is employed here, as in the construction of Fig. 1, but instead of the bevel gear reduction of the Fig. 1 construction a worm is employed upon the shaft 45 which drives a worm wheel 46 carried in the casing 47. In other particulars, the construction corresponds to that of Fig. 1.

In the construction of Fig. 6, the shaft 48 of the motor 49 is arranged vertically instead of horizontally and the runner shaft 50 is driven directly by means of the belt 51 passing around the pulleys 52 and 53. The lower end of the motor shaft 48 is supported in a bearing 54 carried by the framework of the machine, and the weight of the runner is counterbalanced by means of a lever 55 pivoted on the rod 56 and having its outer forked end 57 in engagement with a thrust collar 58 carried by the runner shaft. The arrangement for adjusting the lever 55, including the rod 59 and hand wheel 60 is similar to that heretofore described.

Fig. 7 illustrates still another modification in which the runner shaft 61 is driven directly from the motor 62 by means of the belt 63 passing around the pulleys 64 and 65. The tubular support 66 in which the runner shaft is journaled is provided with laterally extending trunnions 67 having an engagement with the counterbalancing lever 68 corresponding to that in the Fig. 1 construction. The adjustment of the lever is also accomplished in a manner similar to that employed in Fig. 1 by means of the rod 69.

In the modification of Fig. 8, the shaft 70 of the motor 71 is journaled at its lower end in the motor casing with the drive pulley intermediate the supporting bearings for the shaft, the runner shaft 72 being here driven directly by means of the belt 73 as in the Fig. 7 construction. The weight of the runner and shaft is supported by means of a ball thrust bearing 74 carried by the

tubular support 75, and the connection between the lever 76 and the support 75 including the trunnions 77 is the same as in the Fig. 7 construction. A yielding adjustment of the rod 78 is secured by means of the hand wheel 79 threaded on the rod and bearing against the spring 80 which is seated at its upper end against a bracket 81 carried by the beams 82.

From the foregoing it will be apparent that a large number of arrangements might be employed for driving the runner shaft from a motor or line shaft carried by the framework of the machine, and that in all cases convenient means are provided permitting the ready removal of the surfacing unit for replacement or repair. A wide variety of gear reductions is also possible, although those of the type illustrated are preferred. If a motor is employed as a driving means, it is also feasible to mount the motor on the counterbalancing lever as illustrated in Fig. 1, although in general it is preferred to mount the motor upon the framework of the machine rather than upon the lever, and while it is feasible to drive a plurality of machines from a line shaft extending longitudinally of the series, it is in my opinion better practice to have individual driving means, such as an electric motor for each machine.

What I claim is:

1. In combination in a surfacing machine, a framework, a surfacing unit mounted and guided for vertical movement with respect to the framework and comprising a support provided with bearings, a vertical runner shaft journaled therein, and a runner secured to the lower end of the shaft, driving means mounted independent of said unit to one side thereof, counterbalancing means connected to the support, and driving connections between the driving means and said runner shaft, the said unit being releasably supported upon the framework so that it may be removed bodily therefrom.

2. In combination in a surfacing machine, a framework, a surfacing unit mounted for vertical movement with respect to the framework and comprising a support provided with bearings, a vertical runner shaft journaled therein, and a runner secured to the lower end of the shaft, driving means mounted independent of said unit to one side thereof, releasable driving connections between the driving means and runner shaft, means for supporting and counterbalancing said unit comprising a lever having a releasable connection with said support, and means tending to move said unit upwardly.

3. In combination in a surfacing machine a fixed framework for the machine, power means carried thereby, a self-contained surfacing unit comprising a support, a runner,

- and a runner shaft journaled in the support, releasable driving connections intermediate the power means and the runner shaft, a pair of arms one above the other pivoted to the framework and having pivotal releasable connections with said support, and means connected to one of said arms for counterbalancing the unit.
4. In combination in a surfacing machine, a framework, power means carried thereby, a self-contained surfacing unit mounted at one side of the framework and comprising (1) a vertical tubular support provided with spaced bearings, (2) a runner shaft journaled in said bearings and (3) a runner carried by the lower end of the
- shaft, a lever arm pivoted on the upper portion of the framework and having releasable pivotal connection at its outer end with the upper end of said support, guide means carried by the framework below such lever releasably engaging the lower end of such support, adjustable means engaging the inner end of said lever for applying force for counterbalancing the weight of the unit, and releasable driving connections between said power means and said shaft.
- In testimony whereof, I have hereunto subscribed my name this 1st day of June, 1923.

ALBERT E. EVANS.
